ROTARY WEB PRESS

Otto C. F. Meisel, Milton, Mass.

Application February 16, 1933, Serial No. 657,030

3 Claims. (Cl. 101—228)

This invention relates to rotary presses and the object is to provide a web press which will print on the web an immediate succession of impressions of less length than the circumference of the plate 5 cylinder or cylinders. The web thus may be completely imprinted without waste and be cut into sheets of correspondingly short length, folded or otherwise disposed of as may be desired. I obtain this result by the use of a suitable looping mechanism which is readily adjustable to provide for the printing of different sized sheets.

My invention will be well understood by reference to the following description of the illustrative embodiment thereof shown by way of example in 10 the accompanying drawings, wherein:—

Fig. 1 is a diagram of the press;

Fig. 2 is a broken fragmentary view of the mechanism for operating the looper rolls; and

Fig. 3 is a diagram corresponding to part of 15 Fig. 1 and showing a modification.

Referring to Fig. 1 of the drawings, I have there shown a rotary press embodying a plurality of printing couples comprising the plate cylinders 5 and impression cylinders 7. The web *w* drawn 20 from a suitable supply is fed thereto by feed rolls 9 over fixed roll 11, movable looper roll 13 carried on the reciprocating frame 15, and fixed roll 17, leads thence through the printing couples, and leaves the latter over fixed roll 19, movable looper 25 roll 21 carried by frame 15 in fixed relation to looper roll 13, fixed roll 23, and feed rolls 25 which operate in synchronism with feed rolls 9.

The feed rolls 9 and 25 may be suitably driven, as, for instance, by means of change gears to 30 deliver to and withdraw from the press during each revolution thereof a sheet's length of paper of a desired length less than the circumference of the plate cylinders 5 and corresponding to the length of the printing forms thereon. If during 35 the printing operation frame 15 is moved to the left in Fig. 1, roll 21 will draw through the couples slack released by the movement of the roll 13 so as to permit the web to pass through the couples during the printing operation at the same surface speed as the form. After printing is finished and 40 while the web is no longer gripped between the form cylinder and the impression cylinder, movement of the looper rolls to the left may be retarded. They may then be moved back to the 45 right so that roll 13 draws back the web through the forms and also takes up the web which is meanwhile being supplied by the rolls 9 while roll 21 gives up slack to permit the retraction of the web through the forms and to permit the 50 continued operation of the feed rolls 25, delivering

the web from the press at a constant speed. At the end of this retrograde movement the looping rolls may move to the left once again, gradually accelerating the paper extending between them to the speed of the plate cylinder so that when the latter again starts to print, blank paper immediately behind the part previously printed is presented to the form.

Looping mechanism operating generally in the manner above described is disclosed in the patent 65 to Annand 834,602, Oct. 30, 1906, and does not need extensive description. The arrangement there shown, however, requires the use of separate cams for operating the loopers for each sheet length printed and provides for advancing the 70 sheet at a uniform speed by the joint action of the feed rolls and the looper rolls during such fraction of the revolution as is equal to a fraction whose numerator is the sheet length and whose denominator is the cylinder circumference. In 75 contrast therewith I provide a single cam in connection with which an exceedingly simple adjustment provides for handling a wide range of sheet sizes.

I will first describe in a general way the mechanism shown without reference to its theory of operation. Herein the looper frame 15 (see Fig. 2) carries a rack 27 with which meshes a sector 29 operated by a pitman 31 which is oscillated by groove cam 33 which makes one revolution for 80 each revolution of the press. The pitman 31 has an adjustable crank connection with the sector 29, the latter being here shown with a slot 35 along which the end of the pitman may be slidably adjusted to be clamped by the clamp 90 screw 37.

In accordance with my invention I provide for a uniform advance of the web by the looper rolls during a fixed fraction of the revolution of the plate cylinders while the construction is such as 95 to permit the handling of sheets of any length equal to or less than the product of this fraction and the cylinder circumference without changing the machine other than by a simple and readily made adjustment and the necessary change 100 in speed of the feed rolls 9 and 25 to permit them to feed in and out the desired length of sheet.

By way of example and to illustrate one practical construction we may take as this fixed fraction $\frac{1}{6}$ of the circumference of the cylinder, the arrangements then permitting printing a sheet of this or any shorter length. I preferably provide an excess feeding movement to insure that no change of paper speed will occur while the web is gripped by the plate cylinder and for 110

that reason may utilize 260° of the revolution for feeding the paper at the surface speed of the plate cylinders. This provides for 4° at either end which may be considered excess feed. The 5 remaining 100° of a revolution may then be utilized to stop the sheet, to retract it and again to reverse its motion, and conveniently, as in the example herein chosen for illustration, 60° of the revolution may be utilized for retracting movement corresponding to a movement of the rolls 10 13 and 21 to the right in Fig. 1 and 40° to the reversals of movement suitably arranged to prevent shock.

Thus referring to the cam shown in Fig. 2 (the 15 possibility of cutting such a cam will be shown by the analysis to follow later), the arc $a-b-c-d$ may be a smooth spiral corresponding to an advance of the looper rolls to the left at uniform speed. $a-b$, 4° in extent, represents an idle 20 movement or overfeed before the plate cylinder begins to act. The arc $b-c$ is 252° long and during this time printing takes place. Overfeed of 4° is provided at $c-d$. I here show arc $d-e$ as 10° in extent. This period is utilized in reversing 25 the rolls and may, if desired, provide for a retarded movement to the left and/or preferably includes a substantial period of dwell at the extreme of movement to permit absorption of inertia. The arc $e-f$, 60° in length, provides for retracting 30 the paper. Arc $f-a$, 30° in length, provides for reversal with the rolls moving to the right again preferably with a substantial dwell and, if desired, with subsequent acceleration to the left. Since the movement of the rolls to the left is 35 slower than the movement to the right, arc $d-e$ may conveniently as here be shorter than arc $f-a$ and the period of dwell may be shorter. It should be understood that on account of the small scale of the drawing it represents only in 40 a very general way the cam contour.

The arrangement may be best understood by considering first the length of paper moved independently of speed. For convenience in the discussion we may denote the circumference of the 45 plate cylinder as C and the length of paper or sheet length delivered by the rolls 9 and 25 as S . During the $260/360$ of a revolution, therefore, the feed rolls deliver a length of paper equal to $260/360 S$ and, if it is desired to move this through the couples at the same linear speed as the surface speed of the plate cylinder, the length of paper passing through the couples must be $260/360 C$ and the movement of looper roll 21 to the left must then draw through the couples a 50 length of paper equal to $260/360 (C-S)$. Similarly in any retarding movement previous to retraction of the web and while arc $d-e$ of the cam is acting, the looper may draw paper equal in length to P at any suitable variable speed, and similarly if acceleration is provided in the arc $f-a$ the rolls may draw forward a length Q . The 55 total excess movement due to the operation of the looper roll is therefore $260/360 (C-S) + P + Q$. The linear movement of the roll on the frame 15 due to the fact that it operates on the bight of a loop is one-half of this.

Now, referring to Fig. 2, if the throw of cam 33 is t and the pitch radius of segment 29 is 10 inches, the effective crank arm x by means of which pitman 31 must act on the segment defining the position of connection 37 along slot 35 is determined by the following proportion:

$$\frac{1}{2}(260/360(C-S) + P + Q) = \frac{t}{x}$$

75 Now for any given machine all these terms are

constants except the sheet length S and for any value of S , that is, for any given sheet length, will correspond a value of x , that is, a definite position of point of connection of the pitman to the sector which will provide for a proper advance of the looping rolls.

The description thus far has been primarily of the action of the web during 260° of the revolution of the plate cylinder or 260° of the revolution of the cam 33 during the feeding action of the latter. The net desired result of the cooperating action of the feed rolls and the looper rolls is to pass through the couples a sheet length S on each revolution. There passes forward through the couples during the advancing feed a length of web equal to $260/360 C$. The sheet length S has been usefully utilized to receive an impression. We must draw back $260/360 C-S$. During the remaining 100° of the circumference, if any deceleration or acceleration is provided while the loopers still move to the right, the length $P+Q$ is drawn through. Moreover, during this $100/360$ of a revolution the feed rolls 9 will deliver $100/360 S$. We must draw back, therefore, the sum of these quantities, which is $260/360(C-S) + P + Q$, and the linear motion of the looper roll frame is one-half of this. This movement, it will be seen, is identical with the feed motion of the looper rolls. The cam connection 37 remains in the same position along the slot 35 and the path 105 of the cam returns on itself.

Thus by way of example, if we assume a plate cylinder of $4\frac{3}{4}$ inch diameter or 14.92 inches circumference, a throw of 1.4375 inches along arc $a-b-c-d$ of cam 33 (that is, omitting any portion of the throw which may be included in arcs $d-e$ or $f-a$ to effect the retarding and accelerating feeding movements P and Q or alternatively assuming these values to be zero and the arcs $d-e$ and $f-a$ to be circles calling for a dwell 115 of the looper rolls throughout their length) and if we assume a pitch radius of 10 inches for segment 29, then the distance x of the point of connection 37 from the center of motion of the sector for a 7 inch sheet length may be computed from 120 the simplified formula

$$\frac{1}{2}(260/360(C-S)) = \frac{t'}{x}$$

as 5.025 inches and a table might be compiled 125 for other lengths up to .7 of the cylinder circumference, that is, approximately $10\frac{3}{4}$ inches. For a full circumference sheet the segment would be clamped stationary.

As a specific example and assuming the plate 130 cylinder 14.92 as above mentioned and a sheet length of 7 inches, the head of the sheet arrives at the form and for $252/360$ of a revolution moves a distance of 10.444 inches while the cam follower travels from b to c . From c to d the movement continues as an overfeed of .166 inches independent of the sheet length. The head of the sheet may then continue to advance at a variable speed to a distance of $P+.194$ inches, that is, $P+10/360 S$, depending upon the design of the 140 cam, and while the cam follower travels from d to e . During the following 60° the web is fed forward 1.167 inches ($60/360 S$) by its feed roll. At the same time it is drawn backward by the action of the looper rolls $5.72+P+Q$ inches, 145 which may be considered a negative number. Then between points f and a on the cam the web moves forward again .583 inches, that is, $Q+30/360 S$. Finally between a and b there is a forward movement of .166 inches. The alge- 150

braic sum of these quantities is seen to be 7 inches so that at the completion of the cycle the head of the sheet has moved just 7 inches past the bite of the printing rolls and the blank paper 5 immediately following the impression on that sheet is presented ready to be printed on.

In cases of very short sheet lengths it is advantageous to use a double loop, as indicated in Fig. 3, in which the paper leading from fixed roll 10 11 passes over a movable looper roll 13a, hence to a fixed roll 14, back to looper roll 13b, both looper rolls being carried on the reciprocating frame 15, and hence to fixed roll 17 and similarly at the other side of the press. The motion of 15 the looping roll frame is in this instance $\frac{1}{4}$ of the paper feed effected thereby and the momentum or inertia of the motion is thus diminished. Again in the case of a dimension of a 7 inch sheet, if a double loop is utilized, the lever arm 20 through which the pitman 31 acts on sector 29 would be 10.052 inches. Further advantage in double looping is that it keeps the point of connection of the pitman to the segment within a range where better leverage is secured and 25 not within shorter lengths where any error is multiplied in the segment.

I am aware that the invention may be embodied in other specific forms without departing from the spirit or essential attributes thereof, 30 and I therefore desire the present embodiment to be considered in all respects as illustrative and not restrictive; reference being had to the

appended claims rather than to the foregoing description to indicate the scope of the invention.

I claim:

1. In a press in combination with rotary printing means, means for feeding a web to and from the same at speeds less than the surface speed of the plate cylinder, looping mechanism, driving means for effecting during a revolution of the cylinder a uniform motion in one direction and an intermediate retracting motion, and adjustable means for transmitting said motion in desired ratio to the looping mechanism. 80
2. In a press in combination with rotary printing means, means for feeding a web to and from the same at speeds less than the surface speed of the plate cylinder, looping rolls, a rack carrying the rolls, a sector meshing with the rack, a cam rotating in synchronism with the plate cylinder having a spiral arc and an intermediate node and a crank arm connection of adjustably variable length between the cam and the sector. 85
3. In a press in combination with rotary printing means, means for feeding a web to and from the same at speeds less than the surface speed 90 of the plate cylinder, a reciprocable frame having having pairs of rolls thereon, cooperating fixed rolls to permit the web to be trained in a plurality of loops, and means for moving the frame comprising a cam and a lever transmission of 95 adjustable length. 100
